GOLF PRACTICE TARGET

Stanford Bruns, 4888 Kensington Drive, San Diego, Calif.

Filed Aug. 3, 1964, Ser. No. 81,127

Term of patent 14 years

(Cl. D34—5)

FIG. 1 is a perspective view of the golf practice target showing my new design; and

FIG. 2 is a left side view of the target looking in the direction of the arrows 2—2 of FIG. 1.

I claim:

The ornamental design for a golf practice target, as shown.
